UNITED STATES PATENT OFFICE

PAUL BALZE, OF LEONIA, NEW JERSEY, ASSIGNOR TO M. & B. MANUFACTURING CO., INC., OF LEONIA, NEW JERSEY, A CORPORATION OF NEW JERSEY

CONNECTING BRANCH SLEEVE

Application filed January 9, 1929. Serial No. 331,329.

This invention relates to split sleeves for making connections to pipes.

One object of the invention is to provide an improved device of the character described, which can be applied with ease and celerity to any pipe whether for high or low pressure work.

Another object of the invention is the provision of a device of the nature set forth having improved means to engage and hold the same reliably on a pipe.

A further object of the invention is to construct a device of the type mentioned having improved means to take up the contraction of the fusible metal.

A further object of the invention is the provision of a device of the species alluded to having an improved fusible metal member that is readily cast in the device and acts as a unit.

A still further object of the invention is to furnish a split sleeve having a communicating channel therein to permit the fusible member to be cast in remote parts of the fitting with a single pouring of the metal.

Other objects and advantages of the invention will become apparent as the specification proceeds.

With the aforesaid objects in view, the invention consists in the novel combination and arrangements of parts hereinafter described in their preferred embodiment, pointed out in the subjoined claims, and illustrated on the annexed drawings, wherein like parts are designated by the same reference characters throughout the several views.

In the drawings:

Figure 1 is a top plan view of a device embodying the invention, applied to a pipe shown in dotted lines, and with the packing applied.

Fig. 2 is a side elevation of the same.

Fig. 3 is a vertical sectional view taken on line 3—3 of Fig. 1.

Fig. 4 is a horizontal sectional view taken on line 4—4 of Fig. 2.

Fig. 5 is a view of the fusible metal member as the same is cast in the device, but with the latter removed.

The advantages of the invention as here

outlined are best realized when all of its features and instrumentalities are combined in one and the same structure, but, useful devices may be produced embodying less than the whole.

It will be obvious to those skilled in the art to which the invention appertains, that the same may be incorporated in several constructions. The accompanying drawings, therefore, are submitted merely as showing the preferred exemplification of the invention.

Generally described, the invention provides a split sleeve for use in making connections with pipes of various kinds. The invention finds a large application to drainage pipes which are used in buildings. These pipes are made of cast iron with bell and spigot connections; or of galvanized wrought iron with screwed connections, and including certain branch fittings. Where it is desired to make a new connection in an existing plumbing system, it is necessary to break a section of pipe, and remove usually two sections, replacing them by smaller sections among which is a branch fitting. This invention obviates this necessity.

Accordingly the invention provides a split sleeve including a hub member and a back which can be clamped about a pipe or section of plumbing into which a hole has been cut to communicate with the hub member. Preferably the hole is formed by making two spaced saw cuts at right angles to the axis of the pipe, and then removing the metal therebetween along any convenient lines whether straight or curved, but preferably the former, as by means of a chisel, or other suitable tool. Thus a substantially rectangular hole is formed which is easier to make than a round hole. The hub portion of the sleeve has a similar rectangular portion projecting into said hole, and at an angle with the axis of the pipe, according to the well known principles of plumbing design. The space about the projecting hub member is packed with oakum, or the like, and a fusible metal poured thereover within the sleeve. A channel may be formed in the sleeve to permit the metal to flow into the bottom of the

sleeve from the top thereof, thus simplifying this step in the use of the invention. Spacers between the back and hub member are removed after solidification of the metal to permit the sleeve parts to be drawn together to take up the contraction of the fusible metal. The channel referred to may be formed where the spacers are located and the metal solidified therein, to the end that any open crevice 5 or space in the sleeve may be closed by the solidified metal. For carrying out this feature of the invention the spacers are of a sealing character to prevent leakage of the fused metal. There is thus formed an integral metal member including rings around 10 the pipe and serving as an improved means for retention of the fusible metal in the sleeve, and also of the oakum. Since the hub member is greater than a straight angle, it is, by 15 means of the fusible metal member, practically self retained on the pipe.

Referring in detail to the drawings, 10 denotes a device embodying the invention. The device includes a split sleeve 11 having a hub 20 member 12 and a back 13 which are circularly arranged to take about a pipe 14. The hub member 12 includes a connecting portion 15 whereby a branch connection may be effected with the pipe 14. This branch connection may be formed in any suitable manner 25 preferably by casting the same integral with the hub member 12. It is arranged at an acute angle with the axis of the sleeve or pipe 14 so as to discharge thereinto according to the well known principle observed in 30 plumbing design. The connecting portion 15 of the hub member includes a projecting part 16 disposed interiorly of the sleeve and adapted to extend through an opening 17 in the 35 pipe 14 and flush with the interior of the pipe.

The opening 17 may be formed in various ways, but preferably I make two saw cuts at right angles to the pipe and in properly 40 spaced relation to each other, which saw cuts define the upper and lower edges of the opening in the pipe shown in Fig. 2. Thereafter the metal intervening between the saw cuts is removed as, for example, by chipping out 45 with a chisel, thus forming the substantially rectangular opening 17. In practice it is much easier to thus construct the opening than to form a circular one. The projecting part 16 of the hub member is similarly shaped 50 as clearly shown in Fig. 3 so as to conform to the shape of the opening 17 and to substantially fill the same.

The hub member is of an angle greater than 180° for a purpose hereinafter 55 described. Both the hub member and the back are formed with integral lugs 18 and 19 through which bolts 20 are passed to strongly engage together the parts of the sleeve. It will be appreciated that other engaging 60 means may be used in place of the bolts re-

ferred to. Disposed between the adjacent edges of the hub member and back, at the lines of junction of the sleeve parts referred to, are spacers 21 which afford a seal from one end of the sleeve 11 to the other end thereof. The bolts 20 may pass through the spacers and act to simultaneously draw the sleeve parts into closed engagement with the spacers and to reliably retain the spacers in position. These spacers 21 may be formed as separate 70 strips of metal or other suitable material and are readily removable from the sleeve for a purpose hereinafter set forth.

Each of the sleeve parts has a pair of flanges 22 and 23, these flanges extending in 75 the longitudinal direction of the sleeve and being arranged to contact the outer surface of the pipe 14 so as to retain the oakum in its correct position and still permit the parts of the sleeve to be drawn tight after solidification of the fusible metal. The said flanges are disposed in proximity to the lines of junction or spacers 21 and co-operate to form at each side of the sleeve a channel 24 between the wall of the sleeve and the pipe 14. The said flanges terminate at 25 in spaced relation to the upper and lower ends of the sleeve 11.

The space between the sleeve and the pipe 14 between a pair of flanges 22 and a pair of flanges 23 is packed with oakum or the like as shown at 26 and 27, this oakum in the case of the hub member being disposed about the projecting portion 16 and being confined between upper and lower planes 28 and 29 defined by the upper and lower ends of the flange members 22 and 23, respectively.

The upper and lower annular spaces between the sleeve 11 and the pipe 14 and also the channels 24 are filled with a fusible metal as, for example, lead which is poured into the sleeve at the top, thus running through the channels and into the bottom of the sleeve where it is suitably confined. When the metal has solidified it has the form shown in Fig. 5 and includes the upper and lower rings 30 and 31 which are interconnected by longitudinally extending bars 32 that form therebetween openings 33 and 34 within which is enclosed the oakum shown at 26 and 27. The spacers 21 are removed after the fusible metal has set and the bolts 20 drawn tight. It will be readily seen, that this construction will effectively prevent so called "creeping" of the lead joint caused by alternating expansion and contraction of the pipe.

The operation and manner of use of the device will now be clearly apparent. Where it is desired to make a branch connection in an existing plumbing system, an opening 17 is cut in a section of the plumbing as hereinbefore described, and the hub member applied to the section with the projecting portion 16 extending into the opening 17. Then the back is placed up against the hub mem-

ber and bolted thereto by means of the bolts 20 and with the spacers 21 in position. Subsequently the oakum is packed in at 26 and 27, and thereafter a suitable joint runner is 5 put about the pipe at the bottom of the sleeve and the lead is poured in at the top thereof, running through the channels 24 and solidifying in the said channels and also in the upper and lower annular regions in the 10 sleeve. When attaching the sleeve to a pipe in a horizontal position, then a joint runner is used at each end of the sleeve. Thereafter the bolts are loosened or removed depending upon the construction of the spacers 21 and 15 the bolts are again tightened to draw the hub member and back tightly together to take up the contraction in the lead due to solidification thereof. The sleeve 11 is now to all intents and purposes a permanent fixture that 20 can not shift, or be shifted, from its proper location on the pipe, and there is nothing in the way of packing that may fall out 25 therefrom or become leaky due to deterioration as a result of time or weather. The invention thus provides an absolutely leak-proof construction which is well adapted to meet the requirements of the most rigid sanitary code.

I claim:

30 1. As an article of manufacture, a connecting branch having a split sleeve for joining to a pipe comprising a back and a hub member, said members each having an internal length-wise extending flange in proximity to the line of junction of the back and the hub members, said flanges being separated to provide spaces therebetween, the sleeve being adapted to receive a molten fusible metal in the space between the adjacent 35 flanges at the line of junction, the other spaces being adapted to receive a non-metallic backing, said members being adapted to receive spacing means inserted between said members at the lines of junction, said spacing means affording substantially fluid-tight 40 engagement to prevent leakage of said molten metal at the lines of junction, and means to draw said members together upon removal of said spacing means adapted to take up 45 the contraction on solidification and cooling 50 of said fusible metal, with the fusible metal sealing the lines of junction.

2. The article of manufacture as defined in claim 1 in which the flanges terminate in 55 spaced relation to the ends of the sleeve whereby interconnected continuous rings of the fusible metal are formed in the end of the sleeve.

3. A joint construction of the character 60 described comprising in combination with a pipe, a split sleeve branch connection mounted on said pipe, said sleeve connection having a back and a hub member, internally positioned means extending therealong in 65 proximity to and in spaced relation with a

line of junction between said members, a fusible material confined between adjacent portions of said means, non-metallic packing retained by said sleeve against said pipe, said internal means and non-metallic packing, being disposed to permit the fusible material 70 to form a packing ring within the sleeve about the pipe.

4. In a joint construction of the character described comprising in combination with a pipe, a branch connection including a sleeve mounting engaging about said pipe, said sleeve mounting having a back and a hub member, spaced flanges on each of said members extending lengthwise at the interior side of the sleeve mounting and forming spaces between adjacent flanges and the exterior side of the pipe, non-metallic packing material in the spaces between adjacent flanges 75 on the same member and fusible metallic packing in the other spaces as and for the purpose described and specified.

5. A connecting branch including a sleeve portion to engage a pipe, and having a hub to communicate with an opening in the wall 80 of said pipe, said sleeve portion having a flange means on the inner side thereof, said flange means being spaced from said hub on opposite sides thereof, and packing between the pipe and sleeve portion, said packing including non-metallic packing in the region 85 between the hub and the flange means, and cast packing on the other side of the flange means.

6. A connecting branch including a split sleeve for joining to a pipe, comprising sections one of which includes a hub member, flange portions on said sections adjacent to but spaced from and on opposite sides of the lines of junction, and a cast material in said 90 sleeve between said flange portions.

7. In a joint construction of the character described comprising in combination with a pipe, a branch connection including a sleeve mounting engaging about said pipe, said sleeve mounting having a removable section and a hub carrying section, spaced flanges on each of said sections extending lengthwise at the interior side of the sleeve mounting and forming spaces between adjacent flanges and the exterior side of the pipe, non-metallic packing material in the spaces between adjacent flanges on the same section and fusible 100 metallic packing in the other spaces, said flanges and said non-metallic packing terminating in spaced relation to the end portions of the sleeve, said end portions of the sleeve having therein rings of fusible metallic packing material integral with the same material 105 in said other spaces, as and for the purpose described and specified.

110 8. A connecting branch including a sleeve portion to engage a pipe, said sleeve portion having a hub portion to communicate with an opening in the wall of said pipe, said 115

120 125 125

- sleeve portion being provided with a flange means dividing the inner side of the sleeve into zones, said flange means being spaced from said hub portion, and packing between the pipe and sleeve portion, said packing including a yielding packing in the region between the hub portion and the flange means, and cast packing on the other side of the flange means, said flange means including a flange extending longitudinally of the sleeve portion and terminating in spaced relation to the ends thereof, said cast packing including connecting rings extending around the pipe in the ends of the sleeve portion at the ends of the flange.

9. An article of manufacture including a split sleeve engageable around a pipe, said split sleeve having jointed sections one of which includes means for communicating with an opening in the wall of a pipe, a pliable packing in the sleeve extending around said means in spaced relation to the joints between the sections, and cast packing in the sleeve surrounding the pliable packing and extending continuously along said joints for sealing the same.

In testimony whereof I affix my signature.
PAUL BALZE.
